CIRCUIT FOR PRECISION CONTROL OF
MASTER OSCILLATORS

Albert H. Taylor, Washington, D. C., assignor to
Wired Radio, Inc., New York, N. Y., a corpora-
tion of Delaware

Application February 8, 1933, Serial No. 655,829

4 Claims. (Cl. 250—36)

My invention relates broadly to high frequency oscillation systems and more particularly to a circuit for the precision control of master oscillators in a high frequency oscillation system.

5 One of the objects of my invention is to provide a simplified circuit for a high frequency oscillation system which is constructed to deliver oscillations of high frequency and efficiency.

Another object of my invention is to provide 10 a circuit arrangement for a high frequency oscillator and amplifier system having a high degree of freedom from variation in frequency brought about by variations which may occur in plate voltages in the high frequency oscillation system.

15 Still another object of my invention is to provide a high frequency oscillator and power amplifier circuit arrangement having relative simplicity of adjustment by means of direct current meters in the plate and screen circuit of the high 20 frequency oscillation system.

A further object of my invention is to provide a circuit arrangement for utilizing the electrical coupling between the plate and screen electrode in an electron coupled oscillator.

25 A further object of my invention is to provide an arrangement of coupling system between an oscillator and a power amplifier in which the power amplifier has its input system selectively connected either to the plate electrode of a tetrode oscillator or to the screen grid electrode of the tetrode oscillator for securing maximum efficiency in the transfer of energy from the oscillator to the power amplifier while maintaining the frequency of the transferred energy, 30 constant.

Other and further objects of my invention reside in the improved circuit arrangement for the precision control of master oscillators as will be set forth more fully in the specification hereinafter following by reference to the accompanying drawing which diagrammatically illustrates the circuit arrangement of my invention.

I have found the high frequency oscillator and power amplifier system of my invention very 45 practical and stable in its operation. The system has a high degree of ease of adjustment and has a high output efficiency. The high frequency oscillator and power amplifier stages are constituted by tetrodes. The grid of the power amplifier may be excited either by a connection through 50 a stopping condenser to the shield electrode of the tetrode oscillator or by a connection to the plate of the tetrode oscillator. A potentiometer connected across a source of high potential is 55 provided with taps, one of the taps leading to the

screen grid electrode of the tetrode oscillator and another of the taps at higher potential leading to the plate electrode. A high frequency inductance system is connected in circuit between the control grid and the anode. A pair of balancing condensers is connected in series across the inductance and a connection taken from a midpoint between the condensers to a return circuit leading to the cathode. Provision is made for connecting a balance condenser between the screen 10 grid and any point in the coil system. Depending on the internal constants of the particular type of tube used, this point may be either above or below the neutral potential point on the coil system. The purpose of the balance condenser is 15 to neutralize the electrical coupling between the anode and screen grid. One end of the coil system is connected to the control grid and the other end through a stopping condenser to the anode. These ends are opposite in potential. By adjust- 20 ing with the balance condenser the radio frequency potential of the screen grid, the best freedom from reactions, due to tuning of the amplifier circuit may be obtained. This reaction may be reduced to a frequency change of only one or 25 two parts in 100,000—sometimes better.

The next important feature in the circuit is the fact that it is so readily adjusted to guard against variations in the oscillator frequency when the supply voltage is altered. Radio frequency ammeters, not shown in the drawing are 30 ordinarily of course placed in series with the anode and screen grid to determine the current which each one draws, and it has been found that when the direct current potentials of anode 35 and screen grid are so adjusted with respect to each other that the ratio of screen grid current to anode current is about in the ratio of four to five, the circuit is remarkably free from variations due to anode voltage alterations. The 40 changes of frequency due to anode voltage variation of 50% are not more than one or two parts in 100,000.

Referring to the drawing in more detail, the 45 tetrode oscillator is indicated by reference character 1, having cathode 1a, control grid 1b, screen grid 1c and anode 1d. The input circuit of the tetrode oscillator is completed between control grid 1b and cathode 1a through radio frequency choke coil 2 and resistance 3. The cathode 1a is 50 energized from any suitable source of potential as represented generally at 4. The potential for the screen grid 1c and anode 1d is obtained from the potential source indicated at 5, which is electrically connected to the potentiometer 6. A tap 55

1 of selected potential on potentiometer 6 connects through radio frequency choke coil 8 to the screen grid electrode 1c. A tap 9 of higher selected potential on potentiometer 6 connects 5 through radio frequency choke coil 10 to the anode 1d. The high frequency inductance system which is connected with the tetrode 1 is shown at 11. The high frequency inductance system has its terminal bridged by condensers 12 and 14 electrically connected in series. The midpoint 15 between condensers 12 and 14 is connected by lead 16 to the midtap connection 17 of the cathode potential supply transformer 18 leading to the power amplifier tetrode 20. The lead 19 which connects to lead 16 and midtap 17 also provides a return path to the cathode 1a of the tetrode 1. The inductance system 11 has the end 11a thereof connected through lead 21 to control grid 1b. The end 11b of high frequency inductance 11 is connected through stopping condenser 22 to the anode 1d. A balancing condenser 23 is connected between the screen grid 1c and a selected potential point 24 on the inductance 11 intermediate the ends 11a and 11b. The point 24 25 may be either above or below the neutral potential point on the coil system depending upon the internal constants of the particular type of tube used. The balance when adjusted, neutralizes the electrical coupling between the anode 1d and the screen grid 1c.

The power amplifier constituted by tetrode 20 includes cathode 20a, control grid 20b, screen grid 20c and anode 20d. The cathode 20a is energized as heretofore stated through transformer 35 18. Bypass condensers 25 and 26 are connected across the two parts of the secondary winding of transformer 18. The midtap 17 of transformer 18 provides a return path for the anode circuit of the power amplifier 20 through lead 19. Source of potential 5 which supplies anode voltage to the oscillator tetrode 1 also supplies anode voltage to power amplifier 20. The anode circuit of power amplifier 20 includes the resonant circuit 27 constituted by inductance 28 and variable capacity 40 29. Bypass condenser 30 is provided across the source of potential 5 as shown. Potential to the screen grid electrode 20c is supplied from source of potential 5 through resistor 31 connected as shown. A bypass condenser 32 is provided across 45 the screen grid 20c and the cathode 20a as shown. The potential of control grid 20b is controlled from source of potential 33 through the reactance 34 connected with control grid 20b as shown.

In order to simplify the disclosure of my invention, I have shown batteries for supplying the cathode, negative "C", and the anode potentials for the oscillator and power amplifier tubes, but it will be understood that I may employ a power line circuit or motor generator sets for supplying 55 the required operating potential.

A condenser 35 is connected between the control grid 20b of power amplifier tube 20 and the switching device 36. The switching device 36 is movable to either of two contacts represented at 60 37 and 38. Contact 37 is connected through lead 39 to screen grid 1c of the tetrode 1. Contact 38 is connected through lead 40 to the anode 1d of the tetrode 1. Under different conditions greater stability of operation may be obtained by providing the alternative connection which I have shown.

I have found that tuning of the resonant circuit 27 in the output of the power amplifier system does not impair the stability of the oscillator 75 system when connected in accordance with my

invention. The oscillator and power amplifier system of my invention have relatively great freedom from frequency changes, often brought about by variations in anode potentials. The circuits allow relative simplicity of adjustment by means of direct current meters disposed in the anode and screen grid circuit. The oscillator and power amplifier circuit is so arranged that the full realization of the benefits which accrue from the proper adjustment of the potentials on 10 the electrodes of the oscillator and power amplifier tubes is obtained to insure minimum variations in frequency with voltage variation. The natural order of potentials on the screen grid and anode electrodes of the oscillator and power 15 amplifier tubes is such that the condition for high energy and high stability is made to coincide.

While I have described my invention in one of its preferred embodiments, I desire that it be understood that modifications may be made and 20 that I intend no limitations upon my invention other than are imposed by the scope of the appended claims.

What I claim as new and desire to secure by Letters Patent of the United States is as follows: 25

1. A high frequency oscillator and power amplifier system comprising a tetrode including a cathode, a control grid, a screen grid and an anode, a high frequency circuit connected between said control grid and said cathode, a high frequency inductance having one end thereof connected with said control grid and the other end thereof connected with said anode, a balancing condenser, a tap on said high frequency inductance, a circuit extending from said tap through 30 said balancing condenser to said screen grid, means for supplying relatively different potentials to said screen grid and said anode, a pair of condensers disposed in series and connected across said inductance, a tap extending from 35 a central point between said condensers to said cathode, a tetrode constituting a power amplifier, and means connecting the input of said last mentioned tetrode with selected electrodes of the aforementioned tetrode for transferring high frequency oscillations to said second mentioned tetrode. 45

2. A high frequency oscillator and power amplifier system comprising a tetrode including a cathode, a control grid, a screen grid and an anode, a high frequency circuit connected between said control grid and said cathode, a high frequency inductance having one end thereof connected with said control grid and the other end thereof connected with said anode, a balancing condenser, a tap on said high frequency inductance, a circuit extending from said tap through 50 said balancing condenser to said screen grid, means for supplying relatively different potentials to said screen grid and said anode, a pair of condensers disposed in series and connected across said inductance, a tap extending from a central point between said condensers to said cathode, a tetrode constituting a power amplifier, and means for selectively connecting the input circuit of said second mentioned tetrode across the cathode and either said screen grid or 55 said anode of said first mentioned tetrode for effecting the transfer of oscillations to said second mentioned tetrode. 65

3. A high frequency oscillator and power amplifier system comprising a tetrode including a cathode, a control grid, a screen grid and an anode, a high frequency circuit connected between 70 75

said control grid and said cathode, a high frequency inductance having one end thereof connected with said control grid and the other end thereof connected with said anode, a balancing 5 condenser, a tap on said high frequency inductance, a circuit extending from said tap through said balancing condenser to said screen grid, means for supplying relatively different potentials to said screen grid and said anode, a pair 10 of condensers disposed in series and connected across said inductance, a tap extending from a central point between said condensers to said cathode, a tetrode constituting a power amplifier, a switching device having a movable arm connected 15 with the input circuit of said second mentioned tetrode, contacts individual to the anode and screen grid electrode of said first mentioned tetrode, said movable arm being selectively connectible with either of said contacts for effecting

the transfer of energy from said oscillator to said power amplifier.

4. In a high frequency oscillator system, a tetrode including a cathode, a control grid, a screen between said control grid and said cathode, a high frequency inductance having one end connected to said control grid and the other end connected to said anode, means for supplying relatively different potentials to said screen grid and said anode, an adjustable tap on said high 10 frequency inductance, a balancing condenser, a series circuit leading from said adjustable tap through said balancing condenser and to said screen grid, a pair of adjustable condensers connected in series and connected across the ends of 15 said high frequency inductance, and a return path to said cathode connected between said variable condensers.
